UNITED STATES PATENT OFFICE.

HERMAN C. MUELLER AND KARL LANGENBECK, OF ZANESVILLE, OHIO.

TILE-SETTING.

SPECIFICATION forming part of Letters Patent No. 664,169, dated December 18, 1900.

Application filed July 18, 1900. Serial No. 23,457. (No model.)

To all whom it may concern:

Be it known that we, HERMAN C. MUELLER and KARL LANGENBECK, citizens of the United States of America, and residents of Zanesville, in the county of Muskingum and State of Ohio, have invented certain new and useful Improvements in Tile-Setting, of which the following is a specification.

The object of our invention is a tile floor, wall, or ceiling which will not crack either from the settling of the building or from jarring and which may be applied upon ordinary floors or walls without the application of heavy substructures. This object is accomplished by forming the backing of flexible tough material, which while it holds the tile tenaciously in place, yet adjusts itself to a change of the position of the floor.

Figure 1 is a vertical sectional view transverse to the joists of a floor, with the backing and the tile embodying our invention laid thereon. Fig. 2 is an enlarged detail view showing the backing, the tile set therein, and the grouting for finishing up the joints between the tiles. Fig. 3 is a detail view of part of a slab composed of the backing and the tile with a screw for attaching it to a wall.

In Fig. 1 are shown joists *a* and floor *a'*, constructed in the ordinary manner. Upon the floor is laid our backing or foundation *B*, which may consist of a mixture of sawdust, silicate of soda, and whiting, firmly pressed and rammed together and spread evenly upon the floor. To form the surface, pieces *c* of clay tile, glass tile, mosaic tesserae, or other material of a hard resisting character are then pressed into this plastic material, so that some of it rises up in the joints between the pieces. After the tile are so set, to finish the floor the joints that were not filled by the backing material rising up in them are filled with grouting *b* of the same or of a similar flexible material. After standing several hours the backing sets, forming a flexible tough foundation, which holds the tile firmly in place, yet adjusts itself to any change in the floor due to settling of the building without the cracking and consequent disintegrant characteristic of this class of floors heretofore in use that have been formed with rigid backings. This back-

ing also undergoes jars and consequent vibration without cracking, so that with it tile floors may be applied to elevators, boats, and other structures in which tile floors heretofore could not be used successfully because of the vibration to which they are subjected. The floor thus constructed is of comparatively small depth and little weight, so that it may be laid upon floors of ordinary construction without the necessity of changing them or of strengthening their substructure.

For walls and ceilings we prefer slabs, as shown in Fig. 3, composed of the backing and the tiles set therein, which may be attached in place by means of nails or screws *D* or by means of an adhesive cement. After the slabs are attached the joints may be grouted with a flexible material, as described. These slabs may also be used for floors, in this case being attached to the floor of the building by screws or nails and having the joints between them grouted, as aforescribed.

What we claim is—

1. The combination of a flexible cementitious backing combined with a surface made up of pieces of a material of a hard resisting nature bound together at the joints by a material similar to that of the backing, substantially as shown and described.

2. A floor or wall covering made up of a surface composed of pieces of a hard resisting material set into a backing which rises into the joints between the pieces and sets from a plastic to a flexible tough state, substantially as shown and described.

3. The process of forming a floor or wall covering consisting in forming a backing of a material which sets from a plastic to a flexible tough state, of forming the surface thereon by pressing pieces of a hard resisting material into the backing so that it rises into the joints between the pieces and of then filling in the joints with a grouting of a flexible nature.

HERMAN C. MUELLER.
KARL LANGENBECK.
